UNITED STATES PATENT OFFICE.

WILLIAM E. SWANSON, OF WEEHAWKEN, NEW JERSEY.

PULL-CHAIN PENDANT.

Application filed April 12, 1923. Serial No. 631,712.

To all whom it may concern:

Be it known that I, WILLIAM E. SWANSON, a citizen of the United States, and a resident of Weehawken, in the county of Hudson and State of New Jersey, have invented, certain new and useful Improvements in a Pull-Chain Pendant, of which the following is a full, clear, and exact description.

10 This invention appertains to certain improvements in pull chain pendants for electric lamp fixtures and the like, and has for its principal object to provide for a luminous terminal to be suspended from the free 15 end of a pendant chain whereby the same may be readily located at night or in dark places.

Another object of the invention is to provide for a pendant terminal as characterized, and one which will be extremely neat and attractive in appearance, as well as useful in assuring of the positive grip of the hand of a person during the manipulation of the pendant for the accomplishment of 25 its intended purposes, and which is capable of being readily and easily attached to any of the usual forms of flexible pull devices.

With the foregoing and other objects in view, the invention resides in the certain 30 new and useful construction and arrangement of parts as will be hereinafter more fully described, set forth in the appended claims, and illustrated in the accompanying drawing, in which:—

35 Figure 1 is a side elevation of a preferred embodiment of the pendant terminal,

Figure 2 is an edge elevation thereof,

Figure 3 is a fragmentary side elevation of the pendant terminal, and showing the 40 pull chain attachment loop formation at the juncture of the lens clamping band, with the closure cap for the attachment loop removed therefrom,

Figure 4 is a vertical section taken on the 45 line 4—4 of Figure 1,

Figure 5 is a fragmentary edge view of the lens clamping band, and showing the outer end of the pull chain attachment loop thereof in plan, and,

50 Figure 6 is a plan view of the closed end of the closure cap for the pull chain attachment loop of the clamping ring.

Referring to the drawings, the reference letters 10 and 11 designate two identically shaped members, preferably made from a transparent material such as glass or the

like, and of plano-convex or semi-spherical form, substantially as shown.

These members 10 and 11 are to be arranged with their flat faces disposed in abutting relation at the opposite sides of a disc 12, of paper or other similar material, and clamped in such relation by means of a metal clamp band or ring 13.

This band or ring 13 is formed of a single length of metal, preferably a strip of sheet metal bent into the required circular formation to encircle the abutted portions of the members or lenses 10 and 11, with its free ends bent outwardly to provide parallel portions or ears 14 and 15 having openings therein, for the reception of a fastening member or bolt 16, by means of which the band is tightened about the said lenses. The inner circumference of the band or ring 13 between the outwardly bent end portions 14 and 15 thereof is grooved, as at 13', to snugly engage the oppositely curved abutting edge portions of the members or lenses 10 and 11, whereby the latter are securely maintained in position.

In the preferred embodiment of the invention, as illustrated, the angularly bent end portion or ear 14 is made longer than the portion or ear 15 and is bent to form a closed loop 17 with its free end disposed in abutting relation with the outer side of the opposite portion or ear 15, where it is engaged on and secured by the fastening or bolt 16. Formed in the outer end of the loop 17, and opening through one side thereof is a slotted opening 18 for the engagement therein of the free depending end of a flexible or other form of pull chain or element 19 which has its extreme free end knotted or enlarged, as at 19', to prevent the same from disengaging from the loop under direct pulling strains to which the pendant is to be subjected. The lateral disengagement of the connected end of the pull chain or element 19 is prevented by means of a closure cap 20 having its outer closed end provided with an opening 20' through which the pull chain or element 19 is to be threaded prior to its attachment to the loop 17.

100 After the attachment of the pull chain or element 19 to the loop 17, the cap 20 will be snugly fitted over the loop 17 to entirely close the same with the edge of its lower open end abutting the outer side of the 105 clamping band or ring 13 for the purpose.

The paper disc 12, interposed between the

abutted flat faces of the members or lenses 10 and 11, is preferably formed with a cut-out portion 12', of a fanciful design, as for instance, in representation of a crescent moon. When the disc 12, which is preferably opaque, is adhered to the flat face of one of the lenses, this recessed or cutout portion 12', is filled with a paste made from radium powder or the like, so that in the darkness, only the moon portion will be illuminated. However, a plain or uncut circular disc 12 may be employed, if desired, and, in this instance, the same, in its entirety, will be impregnated with an ordinary commercial radium substance or other suitable light emitting compound, whereby the light emanations therefrom will be projected or otherwise visible outwardly through the transparent members or lenses 10 and 11.

20 The lenses 10 and 11 may be made from ordinary transparent material, such as clear or colored glass, or from a glass of any predetermined degree of magnifying power, as desired.

25 Having thus fully described the invention, what is claimed, is:—

1. A pull chain pendant comprising a frame, a pair of parallel laterally projecting ears on said frame, a hook terminal on one of said ears, said hook having in the bend thereof a lateral slotway for reception there-

through of a pull chain, a luminous body carried in said frame, and a bolt passed through said ears for clamping said frame over said body. 35

2. A pull chain pendant comprising a frame formed of a single channeled band of looped configuration, projecting ends on said frame disposed in abutting parallel relation through a portion of their length, one 40 of said ends being longer than the other and curved to form a hook thereover, the bend of said hook having a lateral slotway therein for reception of a pull chain therethrough, a luminous body seated in the channel of 45 said frame, and a bolt passed through the parallel portions of said ends for clamping said frame peripherally over said body.

3. A pull chain pendant comprising a frame formed of a split annular band having laterally projecting parallel ends one of which is longer than the other and bent to form a hook thereover, a luminous body in said frame, said hook having a lateral slotway therein for reception therethrough of a 50 pull chain to dispose the knob terminal of the chain beneath the bend of the hook, means for clamping said frame on said body, and means on said chain for preventing its 55 lateral dislodgment from the slotway in said hook.

WILLIAM E. SWANSON.
